UNITED STATES PATENT OFFICE.

BENJAMIN G. WAGGNER, OF PHILADELPHIA, PENNSYLVANIA.

PREPAYMENT GAS-METER.

No. 880,767.

Specification of Letters Patent.

Patented March 3, 1908.

Application filed April 27, 1907. Serial No. 370,555.

To all whom it may concern:

Be it known that I, BENJAMIN G. WAGGNER, a citizen of the United States, and a resident of Philadelphia, in the county of Philadelphia and State of Pennsylvania, have invented certain new and useful Improvements in Prepayment Gas-Meters, of which the following is a specification.

In the operation of prepayment gas meters it frequently happens that the registering mechanism shows the consumption of more gas than is represented by the value of the coins which are found in the meter. This might imply dishonesty on the part of the collector of coins, but it frequently happens because the gas valve is not tightly closed, so that gas passes through the meter, and this is possible because the gas drives the coin actuated train of parts in the same direction that they would be driven by a coin; in other words, the coin driven train of parts is advanced through the action of gas traversing the meter, because the valve is permitted to remain open by reason of this advancing motion of the coin driven train.

It is the principal object of the present invention to obviate this difficulty and to cause the valve to positively close at the proper time, or else to break or derange some of the parts of the meter, and this breakage or derangement clearly indicates that in such cases the cause of the shortage of coins is the failure of the device and not the dishonesty or negligence of the collector.

To this and other ends hereinafter set forth the invention stated in general terms comprises the improvements to be presently described and finally claimed.

The nature and characteristic features of the invention will be more fully understood from the following description taken in connection with the accompanying drawings forming part hereof, and in which

Figure 1, is an elevational view principally in section of coin receiving mechanism provided with parts embodying features of the invention. Fig. 2, is a sectional view taken on the line *a—a* of Fig. 1, looking in the direction of the arrows. Fig. 3, is a similar view showing the parts in different position. Fig. 4, is a top or plan view principally in section illustrating portions of the meter and showing features of the invention. Fig. 5, is an elevational view showing portions of the meter illustrated in Fig. 4. Fig. 6, is a sectional view of certain of the parts shown in

Figs. 4 and 5, and Fig. 7, is a view illustrating the gas valve.

In the drawings 1, is a knob arranged to be turned backward and forward through a half revolution. Internally it is provided with a shank 2, slotted so as to receive and carry a coin 3, in such position that portions of the coin project. This knob is connected by means of gear wheels 4, with a revoluble shaft 5, that has an opening through it so that when a coin is inserted through the slot 6, it falls through the opening in the shaft 5, and is received by the shank of the knob 1. The gear wheel 7, is provided with a hub 8, that has projecting from it a pair of pins 9, between which the coin passes so that when the coin has been inserted it is carried by the shank of the knob 1, and since it is in between the pins 9, it follows that when the knob is turned the coin acts as a coupling between the knob and the wheel 7, so that the latter is turned. A half revolution of the knob brings the coin opposite the slot 10, through which it freely falls into a proper receptacle. 11, is a detent which prevents retrograde motion of the wheel 7. These parts are not in themselves new and they or their equivalents are common in mechanism for this purpose.

The wheel 7, when it is turned through the intervention of a coin and by the movement of the knob 1, acting through an idler wheel 12 and pinion 13, drives the screw 14. The turning of the screw 14, shifts the nut 15 carried by it toward the right in Fig. 4, thus opening the gas valve 16, because the nut 15 amounts to a carriage 17 which carries a projection 18 that co-operates with a cam shaft arm 19 connected as by a shaft 20 with the arm 21 that carries the valve 16. The carriage 17, carries a toothed wheel 22, that meshes with a long pinion 23, driven as by a shaft and worm gearing 24, from the registering shaft of the meter. After the gas valve 16, has been opened through the coin driven parts, which have been described, gas passing through the meter causes the pinion 23 to be revolved and the pinion 23 turns the wheel 22, which causes the carriage to travel back on its screw until the part or projection 18, co-operating with the part 25 of the lever 19, closes the valve 16. The mechanism last described is not in itself new and is typical only of the general kind of mechanism that is used in a prepayment meter.

It is evident that if the valve 16 should

stick and not close or should otherwise remain open for any cause, gas will continue to pass through the meter and if this should happen the arm 19, would hold the carriage, 5 but the gas would drive the pinion 23 which would drive the wheel 22, but since the carriage is held it may not move and the turning of the wheel 22 rotates the screw 14, which in its turn would drive the wheel 7 in advancing 10 direction; that is to say, in the same direction that it is driven by a coin. However, in accordance with my invention this may not occur because the wheel 7 is held against any turning motion in an advancing 15 direction except that imparted to it by a coin. I accomplish this by providing the wheel 7, or as shown in the drawings its hub 8, with 20 teeth, 28 of which two diametrically arranged are shown. I also provide a pawl or detent 26, pivotally mounted and normally solicited or driven by a spring 27 into engagement 25 with or into position for engaging these teeth 28. The pawl 26 is provided with a tail or projection 28^a disposed in the line of travel of the exposed portion of a coin as it is carried around when the knob 1 is turned. When a coin is in position and the knob 1, 30 is turned the exposed portion of the coin not only lies between the pins 9, but also runs under the tail 28^a and as the knob 1, is turned lifts the tail 28^a, thus lifting the pawl 26 and permitting the wheel 7 to move in an advancing direction. Upon the completion 35 of this movement, any further substantial movement of the wheel 7, is prevented by the pawl 26, so that if the valve 16, should not close tightly and the carriage should be run back, that is toward the left in Fig. 4, the screw 14 could not be driven and under these 40 conditions either one or two things would happen:—either the valve 16 would be forced to close, or else something would have to break, bend or become distorted. In the

first case the operation of the meter would not be interfered with and in the second case 45 it would be apparent that something had gone wrong and that the coin collector had not stolen any of the coin contents of the meter. The provision of means which prevent advancing motion of the wheel 7, or I 50 may say of the coin driven train permits of the advantageous use of a valve 16, having a soft face 29 and a sharp seat 30, because enough pressure can be applied to the valve to surely close it down on its seat, it being 55 understood that if the coin train were free to run in an advancing direction as much pressure could not be applied to the valve as can be done when the described provisions are present. 60

Having thus described the nature and objects of my invention, what I claim as new and desire to secure by Letters Patent is:

In a prepayment gas meter the combination of a manually operated carrier adapted 65 to carry a coin with a portion thereof exposed, a gear wheel which is provided with means that are engaged by the coin and by which advancing motion is imparted to the wheel, a ratchet wheel provided with a pair of 70 diametrically arranged teeth and connected with said gear wheel, and a pawl tending to engage said teeth and prevent advancing motion of said gear wheel and provided with a projection operatively arranged in respect 75 to the coin, whereby the latter when the knob is turned lifts the pawl and permits of advancing motion of the gear wheel, substantially as described.

In testimony whereof I have hereunto 80 signed my name.

BENJAMIN G. WAGGNER.
